J. N. LEWIS

THERMAL SWITCH FOR ELECTRIC IRONS

Filed April 29, 1922

Inventor

James N. Lewis,

By *Richard R. Lewis*

Attorneys

UNITED STATES PATENT OFFICE.

JAMES N. LEWIS, OF DETROIT, MICHIGAN, ASSIGNEE TO LEWIS ELECTRIC MFG. CO. INC., A CORPORATION OF NEW YORK.

THERMAL SWITCH FOR ELECTRIC IRONS.

Application filed April 29, 1922. Serial No. 357,849.

To all whom it may concern:

Be it known that I, JAMES N. LEWIS, a citizen of the United States of America, residing at Detroit, in the county of Wayne and State of Michigan, have invented certain new and useful Improvements in Thermal Switches for Electric Irons, of which the following is a specification, reference being had therein to the accompanying drawings.

This invention relates to an automatic control device for electric irons and the primary object of my invention is to provide an electric iron which will eliminate fires incident to overheated irons being left on an ironing board or other combustible supports. It is a well known fact that a large percentage of fires occur by the operator of an iron neglecting to turn off the current after using the iron or when temporarily leaving the same on an ironing board or other support.

Another object of my invention is to provide a diaphragm control device of general application, but especially designed for an electric iron, the device utilizing the expansive force of a medium for flexing the diaphragm in one direction, and partial vacuum or the inherent retractive force on the diaphragm for flexing it in an opposite direction. As an instance of such diaphragm actuating medium may be cited a liquid or low heat coefficient and by its volumetric displacement cause flexure of the diaphragm.

A further object of this invention is to furnish an iron with a diaphragm control device that will automatically cut on and off an electric current to the iron and thus prevent waste of current and obviate the necessity of the operator of the iron turning on and off a switch each and every time the iron is to be rendered inoperative.

A still further object of my invention is to furnish an iron with a diaphragm control device that may be set at will for desired minimum and maximum temperatures in connection with the iron. For instance, the control device may be regulated to shut off the current to the iron at a maximum temperature and turn on the current at a minimum temperature, thus permitting the operator to set the iron for different kinds of work.

A still further object of my invention is to provide an iron with a switch and a novel leverage mechanism for operating the

switch, the leverage mechanism permitting of the iron being very sensitive to the least fluctuation in temperature, consequently the control of the iron may be regulated to a fine degree as may be essential in connection with various kinds of work.

The above are a few of the objects attained by the simple and durable construction to be hereinafter described, and reference will now be had to the drawing, wherein—

Figure 1 is a horizontal sectional view of the iron;

Fig. 2 is a longitudinal vertical sectional view of the same, and

Fig. 3 is a cross sectional view taken on the line III—III of Fig. 2.

In the drawing the reference numeral 1 denotes an iron body having its upper face provided with a marginal wall 2 and on said base, within said wall, is an electric heating element 3, said element being of the ordinary and well known type including a resistance coil and suitable insulation.

Over the electric heating element 3 is placed a shield 4 made of insulation material, for instance asbestos and this shield has depending side walls 5 resting on the iron body 1 at the outer sides of the marginal wall 2 so as to cooperate with said wall in providing an inclosure or chamber for the electric heating element and thus confine the heat in the lower portion of the iron body, preventing its dissemination in the upper portion of the iron body, and consequently a waste of the energy supplied to the electric heating element.

Extending over the top of the shield 4 is a spider having longitudinal arms 6 and transverse arms 7, the arms 6 having the outer ends thereof connected by screws 8 or other fastening means to the marginal wall 2, and the ends of the arms 7 extend downwardly at the outer sides of the depending walls 5 of the shield 4.

Centrally of the spider is a holder 9 extending into an opening 10 in the shield 4, the holder 9 being directly above the electric heating element and susceptible to the heated air within the chamber containing the heating element. Suitably attached to the holder 9 is a hermetically sealed container or diaphragm device 11 susceptible to expansion and contraction by heat conducted to it by the holder 9 and a detachable filling

plug 12 mounted in said holder, said plug permitting of the container being filled with mercury, oil or any liquid or material having a low coefficient of heat expansion. The device 11 can be conveniently made of two circumferentially corrugated disks or diaphragms having flanged edges secured together to form a chamber or hollow member, and with the lower wall of the member held by the holder 9 the upper wall or diaphragm of the member may be flexed by volumetric displacement of the medium within the member or container.

On the forwardmost arm 6 of the spider 13 is an upright bearing 13 and pivotally connected to said bearing is the forward end of a lever 14, said lever extending rearwardly over the top of the control device 11. Screwed in the lever 14, coaxially of the control device 11, is a contact member 15 having a head 16 adapted to be engaged by a pad 17 centrally of the control device 11. Mounted on the contact member 15 and bearing on the lever 14 is a finger piece 18 locked 25 relative to the contact member 15 by a set screw 19. With the set screw 19 loose the finger piece 18 may be adjusted relative to the contact member said contact member may be adjusted in the lever 14. Such adjustment, however, is limited by either the head 16 contacting with the lower face of the lever 14 or the finger piece 18 contacting with the upper face of said lever. As the contact member 15 is set in Fig. 2, it may be 35 engaged by the pad 17 and the lever 14 actuated to operate a switch.

On the forward arm 6 of the spider and on the marginal wall 2 of the iron body 1 are posts 20 provided with detachable nuts 40 21 employed for positioning and holding a cover 22 on the iron body. This cover has its rear wall 23 provided with a housing 24 and fixed in said housing is an insulator 25 provided with binding posts 26 and contact 45 members 27. Slidable in the insulator 25 is a pin or plunger 28 having a conical head 29 held normally in engagement with the contact members 27 by the expansive force of a coiled spring 30 encircling the plunger 50 28 within the insulator. The upper end of the plunger has a transverse pin 31 engaged by the forked or bifurcated end 32 of the lever 14 so that said lever may raise the plunger 28 against the action of the spring 55 30 or permit the expansive force of said spring to lower the plunger 28.

The housing 24 supports the usual jacks 33 adapted to receive a socket or plug (not shown). One of the jacks 33 is connected 60 by a conductor 34 to one of the binding posts 26 and the other jack is connected by a conductor 35 to the electric heating element

3, which in turn is connected by a conductor 36 to the binding post 26.

Suitably attached to the cover 22 is a conventional form of handle 37 by which the iron may be manipulated.

It is through the medium of the adjustable contact member 15 and the control device 11 that the iron may be set to turn on the electric current when the iron has cooled, for instance one hundred and twenty-five degrees Fahrenheit and turn off the electric current when the iron has heated to the extent of three hundred and fifty degrees 75 Fahrenheit or any limits that may be selected by the user of the iron, but under no circumstances will operation of the iron be permissible at a heat that may cause a fire if the current is not shut off after using 80 the iron. With a very sensitive control device and the advantage of leverage between said device and the switch it is possible to regulate the action of the iron to a fine degree and such degree may be set by the manufacturer so that the iron cannot be conveniently tampered with and its automatic safety feature destroyed.

It is thought that the operation and utility of the electric iron will be apparent without 90 further description, and while in the drawing there is illustrated a preferred embodiment of my invention, it is to be understood that the structural elements are susceptible to such variations and modifications as fall 95 within the scope of the appended claim.

What I claim is:—

In an electrically heated iron having a cover under which is located an electric switch and a thermostatic control device 100 adapted to control said switch and the heating of said iron:—means for supporting said thermostatic control device and mechanism by which said switch may be actuated by said device, said means comprising a four-arm spider under said cover on which is mounted said thermostatic control device, a bearing on one of the arms of said spider at one side of said thermostatic device, a lever pivotally supported by said bearing between 105 said spider and said cover and extending in the direction of another arm of said spider and articulated with said switch, said thermostatic control device being at the juncture of said spider arms and having a portion thereof attached to said spider, and means carried by said lever opposite the attached portion of said control device and extending through said cover adapted for adjustment to regulate the operation of said lever by said thermostatic control device.

In testimony whereof I affix my signature.

JAMES N. LEWIS.
